UNITED STATES PATENT OFFICE.

AMOS H. SMITH, OF BROOKLYN, NEW YORK, ASSIGNOR TO AMERICAN BANK NOTE COMPANY, OF NEW YORK, N. Y., A CORPORATION OF NEW YORK.

FEEDING MECHANISM FOR ROTARY PRINTING MACHINES.

Application filed August 8, 1918, Serial No. 248,517. Renewed April 18, 1922. Serial No. 555,237.

To all whom it may concern:

Be it known that I, AMOS H. SMITH, a citizen of the United States, residing at the borough of Brooklyn, in the city of New York, county of Kings, and State of New York, have invented certain new and useful Improvements in Feeding Mechanisms for Rotary Printing Machines, of which the following is a specification, reference being had therein to the accompanying drawings, which form a part thereof.

My invention relates to feeding mechanisms for rotary printing machines, and more particularly to a mechanism adapted for use with a printing machine of this type using engraved, intaglio, or under-surface printing plates.

Heretofore in printing machines of the type with which the feeding mechanism of my invention is adapted to be used, it has been the practice to feed the sheet of dampened paper directly between the members of the printing couple by a mechanism carried by the feed shelf, or by hand. This practice has resulted in a design of machine in which the elapsed time between the making of the imprint and the delivery of the printed sheet is very brief.

In a machine utilizing the feeding mechanism of my invention, the dampened sheet may be registered upon the feed shelf and delivered upon the printing plate, by a gripper mechanism carried by the impression cylinder, thus permitting such an organization in the structure of the machine as will permit the sheet to remain upon the plate for a greater interval than has been heretofore possible.

To ensure an effective feeding of the sheet, it is essential that the gripper fingers carried by the impression cylinder, or D-roll, lay entirely within, or upon, the plane of the periphery of the D-roll, and be so constructed as to adjust themselves to any irregularities in the plate or plates, while bringing the sheets into printing relation thereto.

A further characteristic of a feeding mechanism made in accordance with my in-

vention, is that when the sheets have been brought with the forward edge thereof between the plate upon the plate cylinder, and the blanket or platen upon the impression cylinder, the grippers release the sheet, subsequent feeding movement thereof resulting from the rotation of the members of the printing couple, the printed sheet being subsequently removed from the plate by a delivery mechanism positioned more or less remote from the printing point, according to the design of machine.

To ensure the proper timely disengagement of the grippers from the sheet, I provide actuating means common to all of the grippers, and so construct the several grippers that the actuation of this means may act differentially thereon, so that none of said grippers may be disengaged from the sheet until after the forward edge of the sheet has been engaged between the members of the printing couple, whereupon all the fingers will instantly follow the plate, thus releasing the paper. By imparting a circular movement to the grippers, during this releasing action, their speed of movement will be relatively greater than that of the plate (which coincides with the speed of the D-roll) and by having this circular movement extend through a sufficiently long arc, a complete disengagement of the grippers with the sheet is ensured, and any tendency of the sheet to follow the D-roll is avoided.

By the differential movement of the several grippers above referred to, no irregularities in the height of the plate can interfere with the actuating mechanism for the grippers, and the instantaneous action of all grippers will be ensured.

A further object of the invention is to provide a simple gripper actuating mechanism, which will impart a timely actuation to the grippers when receiving the sheet, and when releasing it.

The invention consists primarily in a feeding mechanism for rotary printing machines, embodying therein the combination with a plate cylinder, and an impression cylinder or D-roll of a feed shelf, a

plurality of grippers mounted upon said impression cylinder or D-roll, and means adapted to successively close said grippers upon a sheet adjacent said feed shelf, and open said grippers to release the sheet after the forward edge thereof has passed between the printing couple; and in such other novel features of construction and combination of parts, as are hereinafter set forth and described, and more particularly pointed out in the claims hereto appended.

Referring to the drawings,

Fig. 1 is a sectional view of part of a printing couple, showing a feeding mechanism embodying my invention in connection therewith, the positions of the grippers in releasing, and prior to engaging, the sheet, being indicated in dotted lines,

Fig. 2 is an end view of the D-roll showing the actuating means for the grippers; and

Fig. 3 is a perspective view of a portion of the gripper mechanism.

Like letters refer to like parts throughout the several views.

In the embodiment of my invention, shown in the drawings, the printing couple consists of a plate cylinder *a* having mounted thereon an engraved, intaglio, or under-surface printing plate *a'*, and an impression cylinder or D-roll *b* provided with the usual blanket or other impression surface *b'*, and having the usual recessed portion *b*². Adjacent said impression cylinder or D-roll is a feed shelf *c*. The rearward edge of the recess *b*², in the direction of rotation of said roll, is slightly beveled as at *b*³, to afford a gripping area with which the various gripper fingers, to be hereinafter described, operate. The means for securing the blanket or other impression surface, to the D-roll and the actuating means for said D-roll, are not shown, as such are well known in this art, and form no part of the present invention.

Mounted within the recess *b*² is a gripper mechanism adapted to receive sheets from the shelf *c* and convey them into the printing relation to the plate *a'*, suitable means being provided whereby the grippers of said mechanism will receive timely actuations to close them upon the edge of the sheet as it is fed from the shelf *c*, and to open them in a manner to release the sheet after the forward edge thereof has passed between the printing couple; the subsequent feeding movement of the sheet resulting from the actuation of said printing couple. Said gripper mechanism, therefore, merely has the effect of laying the sheet upon the plate and does not co-operate in any way with the delivery mechanism not shown in the drawings, which picks up the sheet from the plate *a'* at a point more or less remote from the printing point.

The gripper mechanism is so constructed as to firmly grip the forward edge of the sheet between the gripper fingers and the portion of the gripping area *b*¹ co-operating therewith respectively, while permitting movement of said fingers in excess of that required to grip the paper, to compensate for irregularities in the surface of the plate, such movement being independent of the actuating means for said grippers. The movement of the grippers independently of their actuating means also facilitates the release of the gripper fingers, irrespective of such irregularities in the plate, and avoids the necessity for any extreme nicety in the adjustment of said fingers in relation to the plate, or in the actuating means for said fingers.

In the form of the invention shown, this gripper mechanism comprises a shaft *e* mounted in the recess *b*² of the impression cylinder or D-roll *b*, said shaft carrying a sequence of blocks *f* mounted thereon so as to be adjustable axially and circumferentially thereof, and to have movement therewith. Each of these blocks has thereon a stop *f*¹ upon one side of the shaft *e*, and a spring seat *f*² upon the other side of said shaft. Pivottally mounted in relation to each block *f* is a gripper finger *g* having a heel *g*¹ adapted to co-operate with the stop *f*¹ and a spring seat *g*² oppositely disposed to the spring seat *f*². A spring *h* is seated between the spring seats *f*² and *g*², and has a normal tendency to hold the heel *g*¹ in engagement with the stop *f*¹. The various gripper fingers *g* are curved as shown, the degree of this curvature conforming more or less to that of the impression cylinder or D-roll *b*, and ensuring the gripper fingers in their entirety being upon, or contained within, the plane of said cylinder when engaging the paper.

The actuating means for the various gripper fingers comprises a rocking lever *i* pivotally mounted upon one of the end plates of the impression cylinder or D-roll *b*, and carrying a segmental gear *i'* meshing with the gear *e'* upon the shaft *e*. The lever *i* has thereon a stud *i*¹ carrying an anti-friction roller bearing upon a stationary cam *j* having a fall *j*¹ adapted to oscillate the lever *i* and the shaft *e* in a manner to close the grippers, and a rise *j*² adapted to oscillate said shaft in a manner to open the grippers. The rise *j*² is preferably more gradual than the fall *j*¹. This cam is so set as to time the closing of the grippers so as to engage the forward edge of the sheet adjacent the feed shelf *c*, and the opening of the grippers so as to release the sheet as it passes from between the plate *a'* and the blanket or other impression surface upon the impression cylinder or D-roll, or when the sheet has reached the printing position in

relation to the plate. Acting upon the lever *i*, to hold the roller upon the stud *i*² in proper relation to the cam *j*, is a spring *k*. This, however, is merely a mechanical expedience, and is not an essential of the invention, it being merely necessary that said roller shall be held in constant contact with said cam.

10 The portions *j*² and *j*⁴ are concentric with the axis of rotation of the impression cylinder or D-roll *b*. The paper sheet is indicated at *m*.

The operation of the herein described mechanism is substantially as follows:—

15 Assuming that the parts are in the position shown in full lines in Fig. 1 of the drawings, with the various gripper fingers *g* in engagement with the forward edge of the sheet, pressing portions thereof against 20 the gripping area afforded by the portion of the blanket or other impression surface *b*' covering the beveled portion *b*², subsequent rotary movement of the plate cylinder *a* and impression cylinder or D-roll *b* will bring the 25 forward edge of the sheet into a position where it will be engaged between the blanket or other impression surface *b*' and the plate *a*'. If by reason of irregularities in the surface of the plate, a portion thereof engages 30 any of the gripper fingers, or in case any of said gripper fingers project slightly beyond the surface *b*', said finger *g* will yield to the pressure thereon from said plate against the tension of the spring *h* acting thereon, thus 35 permitting the gripper fingers to conform to the surface of the plate, the different fingers being capable of this differential movement by reason of the fact that each is spring supported.

40 During this rotation the roll upon the stud *i*² will be travelling upon the concentric portion *j*⁴ of the cam, so that the shaft *e* will receive no movement from its actuating mechanism. Just prior to, immediately 45 after, or substantially simultaneously with, the engagement of the plate *a*' with the sheet of paper *m*, said roller will engage the rise *j*² upon the cam *j*, thus rocking the lever *i* outwardly, and through the segmental gear 50 *i* thereon, imparting a rotative movement to the gear *e*' and the shaft *e*, and to the various blocks *f* thereon. This rotative movement of the blocks *f* will have a tendency, through the springs *h*, to move the various fingers 55 *g* away from their co-operating gripping areas *b*². Such movement, however, is controlled by the engagement of said fingers with the plate *a*'. The movement of the blocks *f* will, however, place the various springs *h* under tension, so that said gripper fingers *g* will follow the plate under the control of their springs, and independently of the shaft *e*. Hence, with the initial divergence of the plate *a*' and the impression surface 60 *b*' upon the impression cylinder or D- 65

roll *b*, the paper *m* will be released by said gripper fingers, and thus have no tendency to follow the impression cylinder.

In following the plate *a*', the various fingers *g* will have a rotative movement in 70 the direction of rotation of the cylinder or D-roll *b*, thus causing them to have movement away from the forward edge, and in the direction of movement of, the paper.

The length of the rise *j*² is sufficient to 75 impart a continuing movement to the shaft *e* until the degree of divergence of the plate *a*' and the surface *b*' is sufficient to permit the fingers *g* to clear the plate, and thereafter to completely reverse the fingers, so 80 as to position them within the recess *b*². Said fingers will remain in this position while the roller upon the stud *i*² is engaging the portion *j*⁴ of the cam, and until said roller reaches the fall *j*' upon the next feed- 85

ing movement.

As the shaft *e* passes the forward edge of the feed shelf *c*, the roller upon the stud *i*² will follow the fall *j*' of the cam *j*, thus imparting a return oscillatory movement to 90 the lever *i* and causing the gear *e*' thereon to reverse the direction of rotation of the shaft *e*, thus closing the various gripper fingers *g* upon the forward edge of the sheet which is projected beyond the edge of the shelf *c* 95 so as to extend parallel with the gripping area afforded by the portion *b*² at the edge of the recess *b*². By having the fall *j*' fairly short, the movement of the gripper fingers in closing upon the sheet, will be fairly rapid, 100 although this fall may be graduated so as to have only the completion of the closing movement occur at the proper interval.

The lever *i* acts against the tension of the spring *h* when said lever is being actuated 105 by the rise *j*², and is actuated by said spring to cause said lever to follow the fall *j*'.

By utilizing gripper fingers, the opening action of which is against spring tension, and the closing action of which is by a positively acting mechanism, the necessity for adjusting each of these fingers to the plate, or plates, upon a machine, is obviated. Furthermore, if any one of the fingers, during 110 the initial opening thereof, encounters an obstruction, the spring *h* upon that finger will yield, thus avoiding any necessity for any extreme nicety in the setting of the actuating means for the several fingers. By so setting the several fingers that they will substantially bear upon the plate when delivering the sheet thereto, the forward edge of the sheet is brought into close proximity to the plate, thus facilitating the application of the sheet to the plate in a manner to permit it to 115 be conveyed thereby to the collecting or delivery mechanism.

It is not my intention to limit the invention to the precise details of construction shown in the accompanying drawings, it be- 120

ing apparent that such may be varied without departing from the spirit and scope of the invention.

Having described the invention what I claim as new, and desire to have protected by Letters Patent, is:—

1. A feeding mechanism for rotary printing machines embodying therein in combination with a plate cylinder, an impression cylinder or D-roll and a feed shelf, of a plurality of grippers mounted upon said impression cylinder or D-roll, and means adapted to successively actuate said grippers to close them upon a sheet at the feed shelf 10 and until after the forward edge thereof has passed the printing couple, and impart a reverse movement to said grippers after the forward edge of the sheet has passed between the printing couple, at a speed to cause them to have movement away from the forward edge of the paper in the direction of movement thereof, and thus release the sheet after the forward edge thereof has passed between the printing couple, and permit it 15 to remain upon the printing plate.

2. A feeding mechanism for rotary printing machines embodying therein in combination with a plate cylinder, an impression cylinder or D-roll and a feed shelf, of a plurality of grippers mounted upon said impression cylinder or D-roll, actuating means adapted to successively close said grippers upon a sheet adjacent said feed shelf, and open said grippers to release the sheet 20 after the forward edge thereof has passed between the printing couple, and permit it to remain upon the printing plate, and means whereby said grippers respectively are adapted to have movement independently of said actuating means, to permit the different grippers to conform to varying surface conditions of the plate.

3. A feeding mechanism for rotary printing machines embodying therein in combination with a plate cylinder, an impression cylinder or D-roll and a feed shelf, of a plurality of grippers mounted upon said impression cylinder or D-roll, actuating means for said grippers, and operative connections between said actuating means and all of said grippers, embodying therein means adapted to rotate said grippers in one direction to close them upon a sheet adjacent said feed shelf and hold them closed until the forward edge of the sheet has passed the printing couple, and to rotate them in the opposite direction and in the direction of rotation of the plate at a speed which will cause them to have movement away from the forward edge of the sheet to release the sheet 55 after the forward edge thereof has passed between the printing couple, and permit it to remain upon the printing plate.

4. A feeding mechanism for rotary printing machines embodying therein in com-

bination with a plate cylinder, an impression cylinder or D-roll and a feed shelf, of a plurality of grippers mounted upon said impression cylinder or D-roll, actuating means common to all of said grippers adapted to successively close said grippers upon a sheet adjacent said feed shelf, and open said grippers to release the sheet after the forward edge thereof has passed between the printing couple, and permit it to remain upon the printing plate, and a spring operative upon each of said grippers, whereby a differential movement may be imparted to said grippers through said actuating means when opening said grippers, and said grippers may conform to varying surface conditions of the plate.

5. A feeding mechanism for rotary printing machines embodying therein in combination with a plate cylinder, an impression cylinder or D-roll and a feed shelf, of an oscillatory shaft mounted in the recessed portion of said impression cylinder or D-roll, actuating means for said shaft, a plurality of blocks carried by, and rotatable with, said shaft, a gripper finger pivotally mounted in relation to each of said blocks, co-operating means carried upon each of said blocks and its associated gripper finger, whereby said fingers may be simultaneously closed upon a sheet adjacent said feed shelf, and a flexible connection adapted to transmit movement from each of said blocks to its associated finger, to release the sheet after the forward edge thereof has passed between the printing couple, and permit it to remain upon the printing plate, whereby each of said fingers may have movement individually of its block to conform to the portion of the plate with which it contacts, and said shaft may have an opening movement while said fingers are in engagement with the plate, without imparting movement to said fingers.

6. A feeding mechanism for rotary printing machines embodying therein in combination with a plate cylinder, an impression cylinder or D-roll and a feed shelf, of an oscillatory shaft mounted in the recessed portion of said impression cylinder or D-roll, actuating means for said shaft, a plurality of blocks carried by, and rotatable with, said shaft, each having a stop upon one side of said shaft and a spring seat upon the other side thereof, a gripper finger pivotally mounted in relation to each of said blocks, and having thereon a heel adapted to engage said stop upon said block, and a spring seat oppositely disposed as to the spring seat of said block, and a sprung seated between said spring seats, whereby said fingers may be simultaneously closed upon a sheet adjacent said feed shelf, and each of said fingers may have movement independently of its block, to conform to the portion

of the plate to which it contacts, and said shaft may have movement while said fingers are in engagement with the plate, without imparting movement to said fingers.

5 7. A feeding mechanism for rotary printing machines embodying therein in combination with a plate cylinder, an impression cylinder or D-roll and a feed shelf, of an oscillatory shaft mounted in the recessed portion of said impression cylinder or D-roll, a plurality of blocks carried by, and rotatable with, said shaft, a gripper finger pivotally mounted in relation to each of said blocks, co-operating means carried upon each of said blocks and its associated gripper finger, whereby said fingers may be simultaneously closed upon a sheet adjacent said feed shelf, a flexible connection adapted to transmit movement from each of said blocks to its associated finger, to release the sheet after the forward edge thereof has passed between the printing couple, and permit it to remain upon the printing plate, whereby each of said fingers may have movement individually of its block to conform to the portion of the plate with which it contacts, and said shaft may have an opening movement while said fingers are in engagement with the plate, without imparting movement to said fingers, and actuating means for said shaft, comprising a gear carried by said shaft, an oscillatory lever having a segmental gear thereon meshing with said first named gear, and a cam having a fall thereon adapted to rock said shaft in one direction to close the grippers, and to rock it in the opposite direction to open said grippers.

8. A feeding mechanism for rotary printing machines embodying therein in combination with a plate cylinder, an impression cylinder or D-roll and a feed shelf, of an oscillatory shaft mounted in the recessed portion of said impression cylinder or D-roll, a plurality of blocks carried by, and rotatable with, said shaft, each having a stop upon one side of said shaft and a spring seat upon the other side thereof, a gripper finger pivotally mounted in relation to each of said blocks, and having thereon a heel adapted to engage said stop upon said block, a spring seat oppositely disposed as to the spring seat of said block, a spring seated between said

spring seats, whereby said fingers may be simultaneously closed upon a sheet adjacent said feed shelf, and each of said fingers may have movement independently of its block, to conform to the portion of the plate to which it contacts, and said shaft may have movement while said fingers are in engagement with plate, without imparting movement to said fingers, and actuating means for said shaft, comprising a gear carried by said shaft, a lever mounted upon said impression cylinder or D-roll, having a segmental gear thereon meshing with said first named gear, and a cam operative upon said lever, having a fall thereon whereby said shaft will be rocked in one direction to close said fingers upon a sheet adjacent said feed shelf, and said shaft will be rocked in the opposite direction to actuate said fingers through said spring after the forward edge of a sheet has passed between the printing couple, and to permit said sheet to remain upon the printing plate.

9. A feeding mechanism for rotary printing machines embodying therein an impression cylinder or D-roll, a feed shelf, an oscillatory shaft mounted in the recessed portion of the impression cylinder or D-roll, gripper fingers adapted to be actuated by said shaft, and actuating means for said shaft comprising a gear carried thereby, a lever mounted upon said impression cylinder or D-roll, and having a segmental gear thereon meshing with said first named gear, and a cam having a fall thereon adapted to actuate said lever to close said grippers upon a sheet adjacent said feed shelf, a dwell therein of sufficient length to hold said grippers in engagement with the sheet until after the forward edge thereof has passed the printing point, and a rise thereon adapted to oscillate said shaft in the opposite direction and at a speed to cause said grippers to move away from the forward edge of the sheet to release the sheet and permit said sheet to remain upon the printing plate.

In witness whereof I have hereunto affixed my signature, this 18th day of July, 1918, in the presence of two subscribing witnesses.

AMOS H. SMITH.
